EDMOND H. LAMBERT, OF PIEDMONT, CALIFORNIA, AND RALPH L. SKINNER, ERIC GEERTZ, AND PAUL WILLIAMS, OF DETROIT, MICHIGAN, ASSIGNORS TO SKINNER AUTOMOTIVE DEVICE CO., INC., OF DETROIT, MICHIGAN, A CORPORATION OF CALIFORNIA

IMPURE OIL RECLAIMER

Application filed March 26, 1928. Serial No. 264,716.

The present invention relates to appliances for purifying or reclaiming used or contaminated lubricating oil by the removal therefrom of gaseous, liquid and solid polluting ingredients, thereby again rendering the oil suitable for further use in motor-vehicle engines, one leading object of the invention being to supply an apparatus of this character which will accomplish the specified results in a safe, economical, efficient and automatic manner.

Stated in a somewhat different manner, one leading purpose of the oil reclaimer or rectifier is to salvage or reclaim the oil drained from the crank-cases of engines used in motor-cars, tractors, etc., by the removal of end points of fuel, water, sludge, carbon, acid, and abrasives, thereby reclaiming the oil and giving it the viscosity and lubricating qualities similar to the original trade stock oil.

To enable those acquainted with this art to fully understand the invention and its various advantages, a preferred embodiment of the invention has been illustrated in the accompanying drawings, throughout the views of which like reference characters have been employed to designate the same parts.

In these drawings:

Figure 1 is a longitudinal vertical section through the greater portion of the apparatus;

Figure 1a is a similar view of the remainder of the appliance;

Figure 2 is a bottom plan view of the rectifier proper of the reclaiming appliance;

Figure 3 is a section on line 3—3 of Figure 2 illustrating the thermostat for controlling the electric circuit;

Figure 4 is an enlarged elevation of the thermostatic appliance partly in section controlling the inflow of oil to the rectifier;

Figure 5 is a vertical section on line 5—5 of Figure 4; and

Figure 6 is a more or less diagrammatic view of the electrical connections of the system.

Referring to these drawings, it will be perceived that the apparatus includes a suitable tank or barrel 21 containing a substantially

smaller inner compartment or tank 22 fitted at its top with a removable cover 23 and provided around its bottom with a plurality of apertures or holes 24 by means of which its contents can gradually drain into the outer receptacle 21 without disturbing the sediment therein in any material degree.

The dirty impure oil to be rectified or purified is poured into the inner container 22 from which it flows into the outer vessel 21, wherein the sediment 25 settles to the bottom, the oil 26, thus freed from such objectionable material, rising to the upper part of the container.

Such settling may be drawn off from time to time through a valve-equipped drain pipe 27 connected to the bottom wall of the tank.

A pipe 28 connects the upper portion of the vessel 21 with the corresponding part of a second tank 29 in which further separation or settling of mechanical impurities occurs, the sediment 31 being drawn off occasionally as circumstances dictate through a similar valve-fitted drain-pipe 32.

A hollow, metal float 33 rides on the top of the clear oil 34, and carries a screen or strainer 35 partly submerged in the oil, such element constituting the inlet to a flexible pipe or hose 36 joined to a pipe 37 connected to the interior of a straining tank 38 outside of a cylindrical screen 39 of appropriate mesh, the inside of the screen being connected by a conduit 41 and a glass sight-gauge 42 to a pipe 43 supplied with a ball-check valve 44.

Pipe 43 connects through the lower portion of the wall of an upright, cylindrical condenser 45 equipped with a number of spaced, vertical tubes 46 extended through upper and lower division walls 47 and 48 respectively, the pipe 43 joining the condenser shell at a point above the wall 48, the upper part of the space around the tubes being connected by a pipe 49 to the bottom end of a heat-insulated preheater 51.

Thus, the impure oil passing through the condenser and around the pipes or tubes 46 lends its cooling and condensing influence on the contents of the latter.

As is clearly shown, the preheater has a number of open-ended, upright tubes 52 ex-

tended through top and bottom division walls 53 and 54, the oil entering the preheater through the conduit 49 flowing upwardly through such tubes and leaving the top of the heater through a pipe 55 which connects with another screening device 56, joined by a pipe 57 to the side of a thermostatic valve structure, characterized as a whole 58, mounted on the underside of the bottom wall of a heated rectifier 59.

The appliance 58, as shown more fully in Figures 4 and 5, has a chamber 61 with which the pipe 57 communicates, and such chamber is traversed by an adjustable, screw-threaded rod 62 extended out through a stuffing-box 63 with its protruding end fitted with a screw-driver slot 64.

Rod 62 has a longitudinal passage 65 for a portion of its length downwardly from its upper end, where it carries a valve-seat member 66, the lower end of the passage having cross passages 67 connecting with the surrounding chamber 61.

A conical valve 68 cooperates with the valve-seat member and is forced to closed position by a coiled spring 69 surrounding its stem and bearing at its lower end on the head of the valve and pressing at its upper end on the shoulder of a cavity 71 accommodating it in a block 72 mounted on the member 58.

As is fully depicted, the stem of the valve extends through the block and central apertures in a plurality of curved, reversely arched, bi-metal, thermostatic members 73, its extreme upper end carrying abutment or stop nuts 74.

As will be noted, these thermostatic elements are inside of the rectifier and their rounded, end portions bearing on one another are slotted and are guided in their movements by a pair of upstanding, stationary pins 75 occupying such slots.

The space 76 above the valve 68 is supplied with an inclined, discharge pipe 77 to deliver the oil into the reclamer in such direction, when the valve is opened by the multiple thermostat against the closing tendency of the spring.

The rectifier 59 comprises an outer housing 78, an inner casing 79, an electric-heater 81 around the lower portion of the latter, an air-jacket shell 82 around the heater, suitable heat-insulating material between the members 78, 79 and 82, an appropriately supported, hollow, cylindrical, baffle 83 inside of casing 79, and an oil-delivery overflow pipe 84 extended up through the baffle member and having an open top end, through which the oil may drain when it reaches such height.

By means described hereinafter, a partial vacuum is maintained in the receptacle 79 by suction applied through a pipe 114 connected to the top of such container and extended

out through the top wall of the housing, such suction drawing the oil into the rectifier through the piping system already described and also conveying away the vapors and gases driven off from the oil undergoing treatment.

The oil in the rectifier is agitated and aerated by a small quantity of hot air admitted to the apparatus, thereby facilitating the distillation operation and assisting in maintaining a uniform temperature throughout the body of oil.

To this end, an inlet-pipe 85 admits outside air into the lower portion of the air-jacket chamber 82, wherein it becomes duly heated by the action of the adjacent electric-heater 81, such heated air leaving the upper part of the chamber through a discharge pipe 86 fitted with a control or regulating valve 87 and a check-valve 88.

Such pipe communicates with the lower part of the chamber 79, so that the air drawn through the jacket and pipe by the partial vacuum in the receptacle 79 enters the latter and in passing upwardly suitably aerates and agitates the oil, the check-valve preventing the oil from flowing into the air-jacket upon cessation of the application of suction to the rectifier.

By reason of suction created by a vacuum-pump 91 driven by an electric-motor 92, the purified oil, freed from its gasifiable and vaporizable contaminating ingredients, such as gasoline and water, by reason of the heat applied thereto under subatmospheric pressure, flows down through the pipe 84 and passes therefrom through pipe 93 into the lower part of that space in the preheater 51 around the tubes 52, where it imparts the greater portion of its heat to the incoming, cooler oil flowing upwardly through such tubes, the thus cooled oil leaving the space specified through a pipe 94 which connects with a pipe 95, supplied with a check-valve 96, leading to the pump, the latter delivering the oil through a pipe 97 into the top of an upright settling tank 98 having a sediment drain-cock 99 at its bottom and having near its top an oil overflow pipe 101 equipped with a horizontally-oscillatory nozzle 102, which is designed to discharge the oil selectively into either of two sets 103, 104 of superposed filters, so that either group may be in operation while the other is having its filter material renewed or replaced.

Each of the superposed filter pans of each group comprises a downwardly-tapered tray or receptacle 105 with an open-work screen or reticulated bottom on which a suitable filter-pad 106 rests, so that the oil delivered to the uppermost tray of the group is filtered through the successive underlying trays and is discharged from the lowermost one into a shallow funnel 107 from which a drain pipe 108 conveys the filtered, rectified oil into a

suitable receptacle 109, such as a barrel or the like.

The filter trays are made with converging side-walls so that as the sheet of filter material, such as wood pulp, is forced down into place, it will be condensed or pressed sufficiently to insure a tight contact with the tray sides, thus necessitating the oil to pass through the filter pad without danger of 10 leakage around its margin.

If desired or required, the interior of the chamber 111 containing the filtering means may be maintained at a suitable temperature by means of one or more electric-heaters 112.

15 Reverting to the pump, it secures its supply of oil for an oil seal and for lubrication purposes, particularly during the initial warming-up period of the still or rectifier 59, from the upper part of the settling tank 98 by 20 means of a pipe 113 appropriately connected to the pump and dipping into the clear oil in the top of the tank, as is fully illustrated.

The gases, vapors and air in the rectifier 59 are drawn off by the suction created by the 25 pump 91 through the pipe 114 joined to the top of the chamber or compartment 79 and delivered into the top of the condenser 45 where all of the liquifiable constituents of the mixture are condensed as they are drawn 30 down through the tubes 46 surrounded by the incoming cold oil, the gases, principally air, not condensed, being drawn or sucked into the pump through a pipe 115 connected to the pipe 95 and delivered through the pump with 35 the oil.

Conduit 114 may conveniently be fitted with a vacuum-gauge 116 which will indicate the operating condition of the pump and the degree of suction in the system.

40 The lower end of the condenser is connected to an automatic separator and intermittent drain 117 similar to the well-known vacuum fuel-feed tank commonly used on automobiles and whose use in connection with oil is shown in United States Patent 1,650,775, thus requiring no further description except to state that it has a baffle 118, and its float and valves deliver the stored condensate, mostly gasoline, kerosene, water, etc., from time to time into a container 119, the non-condensed vapors and gases, principally if not entirely air, flowing on into the pump as specified.

55 The electrical system comprises the three power lines 121, 122, 123 connected to terminals 124 of a three-blade switch 125, 126, 127 housed in a convenient casing 128, the switch being normally retracted or opened 60 by a spring 129 but capable of being moved to and maintained in closed relation by a solenoid 131.

Terminals 132, 133 of the switch are connected through fuses 135, 135 to the electric-heaters 81 and 112 so that whenever and so

long only as the switch is closed the heaters will be in operation.

Terminals 132, 133 and 134 through leads 136, 137 and 138 and appropriate fuses are joined to the electric-motor 92.

70 A starting-switch 139 in a housing 141 has one terminal 142 connected by a wire 143 to one of the switch terminals 124, its companion terminal 144 being connected by a wire 145 to a bi-metal thermostatic electric-switch 146 which by another wire 147 is joined to one end of the solenoid coil, its other end being connected by a wire 148 to the adjacent switch terminal 124.

75 As will be understood, the switch contacts 142 and 144 are adapted to be electrically connected together temporarily by the blade 149.

80 Switch 139 has another pair of contacts 151, 152, the former electrically connected to the contact 144 by a wire 153, and the latter joined by a conductor 154 to the terminal 133 of the triple switch, switch 139 having a second blade 155 co-acting with the contacts 151, 152.

85 The two blades 149 and 155 are mechanically connected together and are adapted to be depressed manually and to move in the opposite direction under the action of spring 156.

90 To start the motor and electric-heaters and leave their continued operation to the control of the thermostatic switch 146, the action of which is subject to the temperature of the oil in the distillation or rectifying chamber 95 79, the operator momentarily depresses the double switch 149—155, thereby closing the circuit 122, 124, 143, 142, 149, 144, 145, 146, 147, 131, 148, 124, 121 and causing the energization of the solenoid which thereupon 100 closes the triple switch 125, 126, 127 and completes the circuits of both the motor and the heaters.

95 As soon as this occurs the operator releases 110 the switch 149, 155 causing the opening of the switch 149 and the closing of switch 155 in series with the middle blade 126 of the triple switch, whereby, when the latter switch opens, it will completely and adequately open the solenoid circuit.

115 If the temperature of the oil in the rectifier becomes excessive because of the lack or retardation of feed of incoming oil thereto, or for any other reason, the switch 146 will 120 automatically open the circuit of the solenoid, causing its deenergization and the automatic opening of switch 125, 126 and 127, thus throwing the motor and heaters out of action.

125 It will be understood, therefore, that when the supply of impure oil to be reclaimed runs out, the appliance will automatically cease operation by breaking all of the electrical circuits.

From the foregoing, it will be plain that the impure oil to be treated is permitted to settle, whereupon it is screened, and heated by condensing the liquefiable constituents of the treated mixture, and then it is further heated in the preheater by the hot treated oil, preliminary to passing into the still or rectifier, where it is aerated, heated and subjected to sub-atmospheric pressure resulting in freeing it from all gasifiable and vaporizable contaminating or polluting ingredients, the gases and vapors being drawn through the condenser wherein they are liquefied and discharged intermittently in a suitable receptacle, the hot oil flowing through the preheater and on to the pump, which not only pumps the oil through the system and causes the needed suction through the appliance, but also pumps the freed unliquefiable air with the oil into the settling tank preliminary to the oil overflowing into the filters.

Hence the three products of the apparatus are the purified, filtered oil free from liquid and mechanical impurities, air, and the condensate.

When the apparatus is first started, the chamber 79 contains cold oil up to the level of the top end of the overflow pipe 84, from the preceding operation of the appliance, and valve 68 is closed.

When such oil becomes properly heated for purifying purposes, the valve 68 is opened by the multiple thermostat against the action of spring 69, allowing a small quantity of oil to enter until the thermostat again permits the spring to close the valve, and the more or less intermittent, and later possibly the continuous, opening of the switch allows the inflow of oil in correct quantity to assure that all of it will be properly and adequately heated.

When the supply of oil becomes exhausted, the temperature of the oil in the still rises enough to cause the thermostat 146 to open the solenoid circuit, whereupon the triple switch opens, thus ending the supply of electrical current to the motor and heaters, the pump of course ceasing operation.

In this way the action of the apparatus is wholly automatic to close down the operation upon exhaustion of the supply of oil to be treated.

From what precedes, it will be understood that undesirable liquid constituents of used lubricating oil, such as acid, heavy unburned fractions of fuel and water are removed by evaporation which is possible because the water and end points of fuel found in used motor oil have lower boiling points than the oil itself.

Evaporation or distillation is effected by applying heat to the liquid while under vacuum, and at the same time aerating it, the effect of the vacuum being to reduce the boiling point of the liquid and the agitation by

the air currents increases the effective surface of evaporation.

Complete evaporation is produced at temperatures lower than the boiling point of the oil making efficient operation possible at a safe temperature, no oil of course being distilled or vaporized.

The result of the removal of liquid dilution and of water from the oil is to restore the body and viscosity to the oil, reducing the acidity and lessening the tendency to emulsify with water.

The removal of solid contamination is accomplished by filtration and the conditions under which the filtering occurs are ideal after the oil leaves the rectifying apparatus since all water which might tend to clog up the filtering medium has been removed and because the high temperature at which the oil is delivered to the filter gives it a low viscosity.

Hence solid matter is easily separated from the oil while in this condition and the oil itself will pass through an extremely fine filter medium at a rate of flow that is practical for commercial operations.

The treatment of the oil is by a continuous process, taking used impure oil from a container, purifying it as it passes through the units of the reclaiming apparatus, and delivering it to the clean oil receiver.

The form of thermostat controlling the inflow of impure oil into the rectifier is not our joint invention and constitutes the subject-matter of another patent application of Ralph L. Skinner, Serial No. 280,737, filed May 26th, 1928.

We claim:

1. In an oil reclaimer, the combination of an oil rectifier, means to admit oil to said rectifier, means to heat the oil in said rectifier, means to admit air into said rectifier to aerate and agitate the oil therein, means to heat said air by said heating means preliminary to its aeration of said oil, and means to apply suction to said rectifier to withdraw the gases and vapors from said rectifier and to maintain said rectifier at a sub-atmospheric pressure.

2. In an oil reclaimer, the combination of an oil-rectifying chamber, means to admit oil-aerating air into said chamber, means to heat the contents of said chamber and to heat said air before its admission into said chamber, a condenser, a preheater, means to conduct impure oil through said condenser and preheater into said chamber, means to deliver the condensate automatically from said condenser, thermostatic means automatically governing the flow of such impure oil into said chamber by the temperature of the oil in said chamber, a pump, means to operate said pump, a connection to permit said pump to suck the gases and vapors from said chamber through said condenser, a connection to

5 permit said pump to feed the purified hot oil from said chamber through said preheater, and thermostatic means to terminate the action of said pump-operating means and said heater automatically upon the occurrence of a predetermined temperature of the oil in said chamber.

10 3. In an oil reclaimer, the combination of an oil-rectifying chamber, means to admit oil-aerating air into said chamber, means to heat the contents of said chamber and to heat said air before its admission into said chamber, a condenser, a preheater, means to conduct impure oil through said condenser and preheater into said chamber, thermostatic means automatically governing the flow of such impure oil into said chamber by the temperature of the oil in said chamber, a pump, means to operate said pump, a connection to permit said pump to suck the gases and vapors from said chamber through said condenser, a connection to permit said pump to feed the purified hot oil from said chamber through said preheater, and means to deliver 25 the condensate automatically from said condenser.

15 4. In an oil reclaimer, the combination of an oil-rectifying chamber, means to supply oil-aerating air to said chamber, means to heat the contents of said chamber, a condenser, a preheater, means to conduct impure oil through said condenser and preheater into said chamber, thermostatic means automatically governing the flow of such impure oil 30 into said chamber by the temperature of the oil in said chamber, a pump, means to operate said pump, a connection to permit said pump to suck the gases and vapors from said chamber through said condenser and to draw the impure oil into said rectifying chamber through said condenser and preheater, a connection to permit said pump to feed the purified hot oil from said chamber through said preheater and to deliver it at atmospheric 35 pressure during the continued application of said suction, and means to deliver the condensate automatically from said condenser.

40 5. In an oil reclaimer the combination of an oil-rectifying chamber, means to heat the contents of said chamber, a condenser, a preheater, means to conduct impure oil through said condenser and preheater into said chamber, thermostatic means automatically governing the flow of such impure oil into said 45 chamber by the temperature of the oil in said chamber, a pump, means to operate said pump, a connection to permit said pump to suck the gases and vapors from said chamber through said condenser and to draw the impure oil into said rectifying chamber through said condenser and preheater, a connection to permit said pump to feed the purified hot oil from said chamber through said preheater and to deliver it at atmospheric pressure during the continued application of said suction,

and means to deliver the condensate automatically from said condenser.

6. In an oil reclaimer, the combination of an oil-rectifying chamber, means to heat the oil in said chamber, means to admit impure oil into said chamber, a pump to apply suction to said chamber, means to operate said pump, means to deliver the rectified oil from said chamber, and thermostatic means to stop the operation of said heating means and said pump-operating means upon the occurrence of a predetermined temperature of the oil in said chamber.

10 7. In an oil-reclaimer, the combination of an oil-rectifier, electric means to heat said rectifier, a filter, electric means to heat said filter, a pump to cause the impure oil to flow through said rectifier and to be delivered to said filter, an electric-motor to operate said pump, and means to break the electric circuits of both of said heating means and said motor upon the occurrence of a predetermined temperature of the oil in said rectifier.

15 8. In an oil-reclaimer, the combination of an oil-rectifying chamber, means to supply oil-aerating air to said chamber, means to heat the contents of said chamber, a condenser, means to conduct impure oil through said condenser into said chamber, thermostatic means automatically governing the flow of such impure oil into said chamber by the temperature of the oil in said chamber, a pump, means to operate said pump, a connection to permit said pump to suck the gases and vapors from said chamber through said condenser and to draw impure oil into said rectifying-chamber through said condenser and to deliver the purified oil at atmospheric pressure during the continued application of said suction, and means to deliver the condensate automatically from said condenser.

20 9. In an oil-reclaimer, the combination of an oil-rectifying chamber, means to admit impure oil into said chamber, means to heat the oil in said chamber, a pump to apply suction to said chamber, means to operate said pump, means to deliver the rectified oil from said chamber and thermostatic means to stop the actuation of said pump-operating means upon the occurrence of a predetermined temperature of the oil in said chamber.

25 In witness whereof we have hereunto set our hands.
